UNITED STATES PATENT OFFICE.

CHARLES D. SEVERANCE, OF GREENFIELD, MASSACHUSETTS.

GEARING.

1,045,200.

Specification of Letters Patent.

Patented Nov. 26, 1912.

Application filed June 5, 1912. Serial No. 701,939.

To all whom it may concern:

Be it known that I, CHARLES D. SEVERANCE, a citizen of the United States of America, residing at Greenfield, Massachusetts, 5 have invented new and useful Improvements in Gearing, of which the following is a specification.

This invention relates to tools and more especially to tools provided with spindles 10 adapted to be driven at different speeds.

One of the objects of the invention is to provide a device of this character in which the change of speed may be readily accomplished.

15 Other objects are to provide a device of this character which is simple in its construction, and therefore not liable to get out of order; which is efficient in use, and which will be comparatively inexpensive to 20 manufacture.

Other objects will in part be obvious, and in part be pointed out hereinafter.

In the accompanying drawing showing 25 an illustrative embodiment of this invention and in which the same reference numeral refers to similar parts in the several figures, Figure 1 is a view in side elevation showing the invention as applied to a breast drill. Fig. 2 is a sectional view on a larger scale 30 taken on the line 2—2 of Fig. 1. Fig. 3 is a part sectional view taken on the line 3—3 of Fig. 2.

In the illustrative embodiment shown in 35 the drawings, the invention is shown as being applied to a breast drill, but it will, of course, be understood that it could be applied to other tools or machines without in any way departing from the spirit of the invention.

40 In the drawings, 1 represents a frame in which is rotatably mounted a spindle 2 provided at its outer end with a chuck 3, of the usual character, adapted to hold the drill bit, and secured to the inner end of the spindle 2 are two bevel gears 4 and 5. A breast plate 6 is supported by the frame in the usual manner, and the frame is also provided with the usual handle 7. The frame is provided with two sockets 8 and 9 which are parallel 45 with one another and which are at right angles to the axis of the spindle 2. These sockets are adapted to receive the axle 10 of a driving wheel 11 which is provided with two concentric rows of gear teeth 12 and 50 13, and which has secured thereto the usual handle 18 by means of which the wheel is

rotated. The parts are so adjusted that when the axle 10 is positioned in the socket 8 the outer gear teeth 12 will engage with the gear 5 on the spindle 2, and the inner gear teeth 13 will be out of engagement with either of the gears 4 and 5 on the spindle. From this it will be seen that as the handle 14 is rotated, a rapid movement will be given to the chuck 3. By placing the axle 10 60 in the other socket 9, the inner gear teeth 13 on the wheel 11 will engage the gear wheel 4 on the spindle 2 and the outer gear teeth 12 will be out of engagement with either of the gears 4 and 5, from which it will be seen 70 that, when the parts are so positioned, rotation of the wheel 11 will cause a slow movement of the chuck 3.

In order to removably hold the axle 10 in position within either one of the sockets 75 8 or 9, the axle is provided with an annular groove 15 with which a locking member 16 adapted to extend through a slot formed in the frame 1 engages. This locking member, as shown, is provided with a finger-piece 17 by which it may be depressed when it is desired to remove or insert the axle, and it is held in its normal or operative position as by means of a spring 18, one end of which engages the finger-piece 17 and 85 the other end of which engages the frame 1. The operation of the device, which should be apparent from the drawings, is as follows: Assuming the wheel 11 to be positioned as shown in Fig. 1, in which position the chuck 3 is adapted to be driven at its high speed, if it is desired to drive the chuck at its low speed, it is merely necessary to depress the finger-piece 17, which will, of course, cause the locking member 16 to 90 move out of engagement with the annular groove 15 in the axle 10, indicated in dotted lines in Fig. 2. The axle may then be withdrawn from the socket 8 and inserted in socket 9, after which, upon relieving the 100 pressure on the finger-piece 17, the spring 18 will cause the locking member 16 to assume its normal or locking position, thereby retaining the axle in place.

Having described this invention in connection 105 with the illustrative embodiment thereof, to the details of which disclosure the invention is not, of course, to be limited, what is claimed as new and what is desired to be secured by Letters Patent is set forth 110 in the appended claims:

1. In a tool, in combination, a frame pro-

vided with two sockets, a spindle rotatably mounted in the frame and two gear wheels mounted thereon, a driving wheel provided with concentrically arranged gear teeth 5 adapted to engage with said gear wheels, said driving wheel being provided with an axle adapted to engage either one of said sockets, said axle being provided with an annular groove, and a locking member extending 10 within said sockets intermediate the ends thereof and adapted to engage said annular groove to lock the axle in position.

2. In a tool, in combination, a frame provided with two sockets, a spindle rotatably mounted in the frame and two gear wheels 15 mounted thereon, a driving wheel provided with concentrically arranged gear teeth adapted to engage with said gear wheels, said driving wheel being provided with an axle 20 adapted to engage either one of said sockets, said axle being provided with an annular groove, said frame being provided with a slot communicating with sockets intermediate their ends and a locking member 25 reciprocatingly positioned within said slot and adapted to extend within said sockets and engage the annular groove in said axle to hold it in position.

3. In a tool, in combination, a frame provided with two sockets, a spindle rotatably mounted in the frame and two gear wheels 30 mounted thereon, a driving wheel provided with concentrically arranged gear teeth adapted to engage with said gear wheels, said driving wheel being provided with an axle 35 adapted to engage either one of said sockets, said axle being provided with an annular groove, said frame being provided with a slot communicating with sockets intermediate their ends, a locking member 40

reciprocatingly positioned within said slot and adapted to extend within said sockets and engage the annular groove in said axle to hold it in position, a finger-piece secured to said locking member for actuating the latter, and a spring engaging said finger-piece and normally holding said locking member in its operative position.

4. In a tool, in combination, a frame provided with two sockets, a spindle rotatably mounted in the frame and two gear wheels 50 mounted thereon, a driving wheel provided with concentrically arranged gear teeth adapted to engage with said gear wheels, said driving wheel being provided with an axle 55 adapted to engage either one of said sockets, said axle being provided with an annular groove, said frame being provided with a slot communicating with said sockets intermediate their ends, a locking member 60 reciprocatingly positioned within said slot and adapted to extend within said sockets and engage in the annular groove in said axle to hold it in position, said frame being provided with an opening extending 65 between said sockets and communicating with said slot, a finger piece positioned within said opening and communicating with said locking member to actuate the same, and a spring operatively connected to said finger 70 piece and normally holding said locking member in its operative position.

In testimony whereof I have signed my name to this specification in the presence of two subscribing witnesses.

CHARLES D. SEVERANCE.
